MOUNTING BRACKET FOR MOTORCYCLE SADDLEBAGS

Aleksis Lahti, Ann Arbor, and Stephen J. Molitoris,
Dearborn, Mich., assignors to American Safety
Equipment Corporation of Michigan, Southfield,
Mich.

Filed Feb. 20, 1967, Ser. No. 5,887

Term of patent 14 years

(CL D90—3)

FIG. 1

FIG. 2

FIG. 3

FIG. 4

FIG. 1 is a top, plan view of a mounting bracket for motorcycle saddlebags, showing our new design.

FIG. 2 is a right side elevational view, the left side being a mirror image thereof.

FIG. 3 is a rear elevational view thereof.

FIG. 4 is a perspective view taken from the rear and left side.

We claim:

The ornamental design for a mounting bracket for motorcycle saddlebags, as shown.
